UNITED STATES PATENT OFFICE.

CHARLES E. WADE, OF EAST ORANGE, NEW JERSEY.

SOAP-DISPENSER.

962,682.

Specification of Letters Patent. Patented July 23, 1910.

Application filed September 1, 1908. Serial No. 451,167.

To all whom it may concern:

Be it known that I, CHARLES E. WADE, a citizen of the United States, residing at East Orange, in the county of Essex and State of New Jersey, have invented certain new and useful Improvements in Soap-Dispensers, of which the following is a full, clear, and exact description.

My invention relates to soap dispensers, particularly of that type in which a quantity of liquid soap or compound is stored in a reservoir or receptacle having means for suitably discharging small quantities when desired.

15 It is the purpose of my present invention to improve and simplify apparatus of this class, and attain the discharge of the soapy liquid in as convenient and positive a manner as possible.

20 In carrying out the invention I provide means by which the soapy liquid is positively acted upon in its ejection from the reservoir, not depending on gravity for its impelling force at any stage of the operation. I consider this an important characteristic of the invention, as the liquid is sometimes thick and viscous and does not run freely through narrow passages where there is no other impelling force than the 25 slight pressure due to the weight of the small fluid column available. I make use of a form of pump mechanism having valves and I further provide a form of automatic or check valve for controlling the inlet opening of the reservoir. I have illustrated specially constructed valves having special advantages, as will be later more fully set forth.

Having these various and other objects in view, my invention consists in the features of construction and combination as herein-after set forth and claimed.

In the drawings: Figure 1 is a side elevation, partly in section, of a soap-dispenser embodying the principles of my invention; Fig. 2 is a detail sectional view of the valve which controls the inlet or feed orifice, and Fig. 3 is a similar view showing a slightly modified construction.

50 Referring to the drawing in which like parts are designated by the same reference sign, 1 designates a receptacle or vessel conveniently made of glass and inset and ce-

mented in or otherwise attached to the supporting base 2. The receptacle 1 may be 55 made of any desired form or outline, but I prefer the dome shape shown, as being particularly convenient and ornamental in use. The base 2 is conveniently made in the form of a bracket with ears 3 which can be fastened upon a wall or supporting surface by screws 4. Within the base 2 is contained a pump mechanism for ejecting the soapy liquid.

The receptacle 1 has an opening 5 at its 65 upper end in which is received a small metallic or other cage 6 adapted to contain and guide the inlet valve. I make the cage 6 with a flange or shoulder 7 adapted to contact with the interior surface of the receptacle 1 around the opening 5. The upper exterior portion of the cage 6 is threaded to receive a nut or collar 8 which can be screwed down on the cage so as to coöperate with the flange 7 and firmly hold the cage in 75 its place. The cage 6 is of generally thimble shape, closed at its lower end 9 and having slots or openings 10 adjacent thereto which establish a free communication to the interior of the receptacle 1.

80 11 designates a ball or other valve supported within the cage 6 and impelled upward by a spring 12. I have shown a cup-shaped valve 11 and a form of spring 12 having a reduced end 13 which enters the 85 interior of the cup 11 so as to retain the same in its central position.

14 designates a cap having an interior threaded portion 15 adapted to screw upon the upper threaded extremity of the cage 6. 90 and having an opening 16 with a beveled edge, which coöperates with the valve 11. It is evident that when the cap or cover 14 is screwed into place, the receptacle is given a finished and ornamental outline, and 95 at the same time a convenient valve seat is provided. The soapy liquid may be supplied by pouring it into the valve opening 16 from a vessel having any suitable discharge spout, the valve 11 being depressed into its cage in 100 this action. The base 2 is chambered or recessed transversely inward from its exposed side with a cylindrical bore 18 which constitutes the barrel or cylinder of the pump.

19 designates a passage extending upward 105 from the pump bore 18 into the receptacle

1, and through which the soapy liquid may enter the pump chamber.

20 designates a plunger made comparatively long in practice and having a piston-rod 21 with a thumb-button 22 which can be depressed to impel the plunger 20 inward.

23 denotes a cap screwed upon a threaded extremity 24 of the base 2 and adapted to inclose packing material 25, if desired, thereby constituting a gland for the piston rod. The plunger 20 is normally impelled to its outer position shown in Fig. 1 by a spring 26 contained within the bore of the pump chamber. At its inner end the pump bore is narrowed to form a chamber 27 for the valve 28. I make the valve 28 similar to the valve 11, already described, in the form of a cup-shaped, sheet metal part impelled by a spring 29 having a reduced extremity 30 which enters the cavity of the cup.

31 designates a perforated disk or washer constituting the valve seat for the valve 28, being fixed within the pump bore or recess at a suitable point for this purpose. This plate or washer is also adapted to constitute an abutment for the spring 26. 32 designates a discharge spout or nozzle having a passage 33 which communicates with the interior chamber 27 of the pump.

30. In use the receptacle 1 is filled with the soapy liquid or compound through the opening 16, as already described. When it is desired to obtain a quantity of the soapy compound, the button 22 is depressed, forcing the plunger 20 inward and compressing the liquid in the space 26 past the valve 28 and outward through the discharge nozzle 32. In this action the opening 19 is closed by the plunger itself as soon as the latter has moved through a slight range of its movement, so that thereafter the ejection of the soapy compound is accomplished with absolute positiveness. When the plunger 20 starts to return, a partial vacuum is created in the pump bore or chamber on account of the immediate closure of the valve 28 by its impelling spring. Into this vacuum the soapy compound is quickly forced by atmospheric pressure through the opening 19 as soon as the latter is uncovered by the movement of the plunger. The pump chamber is thereby immediately filled with a new supply of soapy compound without depending on gravity or other factor of such uncertain character or magnitude.

55. In Fig. 3 I have illustrated a slightly modified construction of inlet valve in which the nut or collar 8 is dispensed with. In this case the cap 14 screws directly upon the upper threaded end of the cage 6 and constitutes the retaining means therefor in addition to its function as a valve seat. In other respects the construction of Fig. 3 is

similar to that of Fig. 2 and need not therefore be more particularly described.

65

What I claim is:—

1. In a soap dispenser, a receptacle, a base for said receptacle having a pump bore and also a port leading from said receptacle to said bore, a plunger in said bore, means for normally forcing said plunger to its outermost position, a perforated disk having the perforation therein in substantial alignment with the axis of said plunger, a check valve normally closing said perforation, said base having a recess therein in which said valve is disposed, and a downwardly projecting nozzle opening into said recess, said plunger being movable toward said disk and the arrangement of the above recited parts being such that the initial movement of the plunger closes the port from said receptacle, the fluid in said bore being positively ejected by the continued advance of said plunger through said disk and out of said nozzle, in close proximity to the hand of the operator, the axial position of the check valve preventing gumming up of the same by the ejected fluid.

2. In a soap dispenser, a receptacle, a base therefor having a pump bore and having a passage establishing communication between said bore and said receptacle, a plunger movable in said bore and having an initial position just uncovering said passage, said plunger having a predetermined stroke and a length greater than such stroke whereby it constitutes a piston valve to close said passage, a discharge nozzle for said bore, a perforated disk at the inner end of said bore, a recessed member normally closing the perforation of said disk, and a spring maintaining said part in such relation, said spring having a reduced portion entering said part to center the latter.

105

3. In a soap dispenser, a receptacle, a base therefor having a pump bore and having a passage establishing communication between said bore and said receptacle, a plunger movable in said bore and having an initial position just uncovering said passage, said plunger having a predetermined stroke and a length greater than such stroke, whereby it constitutes a piston valve to close said passage, a discharge nozzle for said bore, a perforated disk at the inner end of said bore, a cup-shaped sheet metal part normally closing the perforation of said disk, and a spring maintaining said part in such relation, said spring having a reduced portion entering said part to center the latter.

4. In a soap dispenser, a dome-shaped receptacle with a check valve at its upper end, a base therefor having a horizontal pump bore and having a passage establishing com-

110

115

125

munication between said bore and said receptacle, a plunger movable in said bore and constituting a piston valve to close said passage as soon as said plunger commences its inward stroke, an inclined, forwardly projecting discharge nozzle for said bore, a removable perforated disk at the inner end of said bore, a cup-shaped sheet metal part normally closing the perforation of said disk, and a spring entering said part and

pressing the latter against the perforation of said disk, and means for operating said plunger disposed adjacent the orifice of said inclined nozzle.

In witness whereof, I subscribe my signature, in the presence of two witnesses.

CHARLES E. WADE.
